SLEEVE HEAD PAD FOR GARMENTS

Irving A. Danilin, New York, N. Y.

Application March 2, 1946, Serial No. 651,510

4 Claims. (Cl. 2—268)

1

This invention relates generally to the clothing art and more particularly to improvements in shoulder pads or sleeve head pads.

In the manufacture of coats and jackets, and similar garments having a shoulder portion with an armhole opening, and a sleeve connected to the edge of said armhole opening, pads are used to soften or increase the radius of the fold or bend in the fabric as it leaves the upper edge portions of the arm hole opening to fall downwardly to form the sleeve of the garment.

While pads have been used for this purpose in the past they have been either of such soft construction that they tend to bunch, mat or become lumpy when worn or they have been of a character wherein woven fabric is used in which event they lack the desired softness and resiliency and the cost thereof is relatively high. The soft pads, further, are open to the objection that they tend to disintegrate when the garment is subjected to repeated cleaning operations.

It is therefore among the objects of the present invention to provide improved shoulder or sleeve head pads for garments, composed of felt providing the desired softness with adequate stability.

Another object herein lies in the provision of structure of the class described which may be more readily sewn or otherwise attached to the garment with which it is to be used.

A still further object lies in the provision of shoulder or sleeve head pads for use with garments in which the use of a bias fabric strip is eliminated.

A feature of the invention lies in the fact that the present constructions may be utilized with garments of various weights so that, for example, the present pads in a lighter weight may be used on women's garments or men's garments made of light weight cloth.

A feature of the invention lies in the fact that by the use of my improved pad the external appearance of the shoulder head is enhanced.

Another object herein lies in the provision of structure of the class described in which a minimum of material is used so that the garment is comfortable when worn.

These objects and other incidental ends and advantages will more fully appear in the progress of this disclosure and be pointed out in the appended claims.

In the drawings in which similar reference characters designate corresponding parts throughout the several views:

Figure 1 is an enlarged fragmentary vertical

2

sectional view showing a first embodiment of the invention as installed in the shoulder portion and sleeve head of a garment.

Figure 2 is a view in perspective of a blank of felt in one stage of the manufacture of my improved pad.

Figure 3 is a view corresponding generally to Figure 2 but showing the blank in ensuing stages of the fabrication thereof.

10 Figure 4 is an enlarged vertical sectional view as seen from the plane 4—4 on Figure 3.

Figure 5 is a fragmentary view in perspective showing the two blanks which go to make up the second embodiment of the invention in a stage in the manufacture thereof.

15 Figure 6 is a view corresponding to Figure 5 but showing the blanks in ensuing stages of the fabrication thereof.

Figure 7 is an enlarged vertical sectional view as seen from the plane 7—7 on Figure 6.

Figure 8 is a fragmentary view in perspective showing the two blanks which go to make up the third embodiment of the invention in a stage in the manufacture thereof.

20 Figure 9 is a view corresponding generally to Figure 8 but showing the blanks in ensuing stages of the fabrication thereof.

Figure 10 is an enlarged vertical sectional view as seen from the plane 10—10 on Figure 9.

25 Turning now to the first embodiment of the invention illustrated in Figures 1 to 4 inclusive, the shoulder or sleeve head pad generally indicated by reference character 10 is formed from a single blank 11 composed of felt. The felt blank 11 may in turn be composed of an agglomeration of fibers having felting characteristics such as cotton or wool or combinations thereof together with such sizing and binding agents as are necessary, such being well known in the felt manufacturing art.

30 The blank 11 is preferably oblong and includes first and second lateral edges 12 and 13 and end edges 14 and 15. The blank 11 has first and second principal surfaces 16 and 17 which are preferably substantially smooth. The distance between the first and second lateral edges 12 and 13 is governed by the desired distance between the fold edge 20 and the edge 13 in the finished pad. Disposed at a distance from the lateral edge 12 preferably substantially equal to one third of the distance between the lateral edges 12 and 13 is a fold line 18 and in the fabrication of the pad 10 the blank 11 is folded about the line 18 and the convex portion of the fold 20 occurring on the surface 16. This folding operation is seen in process in the left portion of Figure 3. After the

35

fold 20 has been formed the portions 21 and 22 are interconnected by the line of stitches 23 which prevents the portions 21 and 22 from shifting with respect to each other.

The finished pad presents a neat appearance and may be readily secured to the desired portion of the garment by suitably positioned stitches such as the stitches 25. Depending upon the area in which the greatest amount of padding is desired, the pad may be mounted at the juncture of the arm hole opening of the sleeve head with either the fold edge 20 or the second edge 13 outermost, that is, disposed most distant from the neck opening of the garment.

In the second embodiment of the invention illustrated in Figures 5, 6 and 7, the shoulder or sleeve head pad is generally indicated by reference character 110 and is formed from two separate blanks 111 and 131. The blanks 111 and 131 are composed of felt or a collection of fibers having felting characteristics such as cotton or wool or combinations thereof together with such binding, adhering or finishing materials as are necessary, such being well known in the felting art. The blanks 111 and 131 are preferably oblong, the blank 131 being of lesser width than the blank 111. The blank 111 has first and second principal surfaces 116 and 117 which are preferably substantially smooth. The distance between the first and second lateral edges 112 and 113 is governed by the desired distance between the fold edge 120 and the lateral edge 113 in the finished pad. Disposed at a distance from the lateral edge 112, preferably substantially equal to one third of the distance between the lateral edges 112 and 113 is a fold line 118 and in the fabrication of the pad 110 the blank 111 is folded about the line 118, the convex portion of the fold 120 occurring on the surface 116. The blank 131 has first and second principal surfaces 136 and 137 which are preferably smooth. The distance between the first and second lateral edges 132 and 133 is governed generally by the distance between the fold edge 120 of the blank 111 and the lateral edge 112, said blank 131 being substantially twice that distance in width. The blank 131 has a fold line 138 which longitudinally bisects the said blank and is adapted to become aligned with the fold line 118 when the blanks 131 and 111 are placed together.

In assembling the blanks 111 and 131, the blank 131 may be placed upon the blank 111 with the edge 132 in alignment with the edge 112. The two blanks are then simultaneously folded along the respective fold lines 138 and 118 and in such folded condition are secured by a row of stitches 123 which extends through the four laminations thereby formed.

In the second embodiment there are thus four layers of material along one longitudinal area of the device and only a single thickness of the material extending along a laterally adjacent area. This is seen, for example, in Figure 7. By this construction accentuated thickness and weight are provided in one longitudinal area. The thickened area is formed by a plurality of laminations which may shift slightly with respect to each other in conforming the pad 110 to the desired curvature and yet the parts are prevented from an undue amount of displacement by the stitching 123.

Turning now to the third embodiment of the invention illustrated in Figures 8 to 10 inclusive, the shoulder or sleeve head pad is generally indicated by reference character 210 and is formed from two separate blanks 211 and 231. The

blanks 211 and 231 are composed of felt or similar non-woven material in which the fibers are interconnected. The blanks 211 and 231 are preferably oblong and of substantially the same size.

5 The blank 211 has first and second principal surfaces 216 and 217 while the blank 231 has first and second principal surfaces 236 and 237. Each of the blanks is of a width substantially 50% greater than the total width of the finished article, and each of said blanks has a fold line, said lines being indicated by reference characters 218 and 238. The distances between said fold lines and the edges 213 and 233 are substantially equal to the desired width of the finished article.

15 In fabricating the finished device, the blank 231 is placed upon the blank 211 and the both of them are simultaneously folded about the lines 238 and 218, the fold being secured in place by the rows of stitches 223 and 253.

20 The third embodiment of the invention differs from the second embodiment principally in the fact that the relatively thinner area of the device 210 contains two plies of material. This portion is indicated by reference character 251 on Figure 10. Further, in the third form, undesired displacement of the laminations forming the heavier portion 250 is prevented by the stitches 223 and 253.

25 It may thus be seen that I have provided novel and useful shoulder and sleeve head pad constructions which may be economically and rapidly fabricated and which are easily adapted and secured in place upon the garment portions with which they are associated. As is well known in the art to which the present invention relates my improved pads may be shifted about in position with respect to the garment to produce the desired bulk or softness in predetermined areas of the garment. By virtue of the fact that the material 30 of which my pads are composed is felt or material of substantially similar nature, the pads are prevented from undesirably bunching, matting or shifting in position and the installation stitching may be easily and securely put in place.

35 45 I wish it to be understood that I do not desire to be limited to the exact details of construction shown and described for obvious modifications will occur to a person skilled in the art.

I claim:

50 1. A shoulder or sleeve head pad comprising: a plurality of separate elongated strips of felt, each of said strips being folded about a predetermined line thereon, said last mentioned lines being aligned and juxtaposed; and stitch means extending through and securing together the several laminations formed by said strips in the folded condition thereof.

55 2. A shoulder or sleeve head pad comprising: a pair of separate elongated strips of felt, each of said strips being folded about a predetermined line thereon, said last mentioned lines being aligned and juxtaposed; and stitch means extending through and securing together the several laminations formed by said strips in the folded condition thereof.

60 65 3. A shoulder or sleeve head pad comprising: a plurality of separate elongated strips of felt, each of said strips being folded about a predetermined line thereon, which is closer to one of its longitudinal edges than to the remaining longitudinal edge thereof, said last mentioned lines being aligned and juxtaposed; and stitch means extending through and securing together the several laminations formed by said strips in the folded condition thereof.

70 75 75

4. A shoulder or sleeve head pad comprising: a plurality of separate elongated strips of felt, one of said strips being narrower than the remaining; each of said strips being folded about a predetermined line thereon, said last mentioned lines being aligned and juxtaposed; and stitch means extending through and securing together the several laminations formed by said strips in the folded condition thereof.
